UNITED STATES PATENT OFFICE.

BENJAMIN C. POLE, OF CAMDEN, NEW JERSEY.

TRIPLEX MOTOR FOR STREET-RAILWAYS.

SPECIFICATION forming part of Letters Patent No. 365,273, dated June 21, 1887.

Application filed May 20, 1886. Serial No. 202,771. (No model.)

To all whom it may concern:

Be it known that I, BENJAMIN C. POLE, a citizen of the United States, residing at Camden, in the county of Camden, State of New Jersey, have invented certain new and useful Improvements in Triplex Motors for Street-Railways, of which the following is a specification, reference being had therein to the accompanying drawings.

10 My invention consists in construction in and to the foot action; also in certain construction necessary to the driving-wheel action, so as to enable the driver of the motor to apply more or less power to the driving-wheels; and it consists in the construction of a friction-brake having certain useful functions.

The invention further consists in a means of preserving the foot actions from wear and tear of the streets and the dirt and dust of the same; also, in certain constructions of the feet, whereby they may be kept warm in winter, thereby preventing them from becoming ballded, and thus unable to hold upon the ground; and, further, in providing them with calks, which may be sharpened in slippery weather; also, in constructions by which the flow of gas is made to first leave a high-pressure tank and thence into two pressure-regulators, from thence to a water-locked gasometer, thence to an elastic bag, and thence to a gas engine, which is the motive power of the motor, and in constructions whereby the high-pressure gas is made to pass the before-mentioned pressure-regulators, and then to divide into two streams of gas, one, as hereinbefore stated, to supply a gas-engine, and the other to supply the lights of the said gas-engine, as will hereinafter be set forth; also, in constructions whereby the feet will be maintained in good form and shape, notwithstanding they are distorted and compressed at each footstep of the motor; also, in a system of balancing the before-mentioned foot actions; also, in constructions of the friction-devices of the motor, which will allow of speedy adjustment of the friction-brake when the same may become worn; also, in a construction of a T-joint in the foot action to enable the foot to be placed squarely on the ground; the above construction being improvements on Letters Pat-

ent of the United States No. 103,625, May 31, 1870; No. 116,610, July 4, 1871; No. 117,307, July 25, 1871; No. 137,421, April 1, 1873, and patent granted to me, No. 335,479, February 2, 1886.

By reference to the drawings and letters of reference marked thereon it will be seen that Figure 1 represents a sectional side elevation of my triplex motor. Fig. 2 is a back view of my foot action for the motor. Fig. 3 is a top plan of the rubber cushion of the foot action. Fig. 4 is a side elevation of Fig. 3. Fig. 5 is a sectional elevation on line *x* *x* of Fig. 2. Fig. 6 is a part sectional elevation of the double gas-regulators, showing a means of dividing the stream of city pressure-gas, after it has been regulated, from a tank of high-pressure gas. Fig. 7 is a view on line *x* *x* of Fig. 2, and further shows a necessary bend of the T-joint of the foot action. Fig. 8 is a side elevation of the friction device of the motor. Fig. 9 is a sectional side elevation of Fig. 8 on line *w* *w*. Fig. 10 is a perspective view of the friction-brake shoe. Fig. 11 is a sectional view of the brake-shoe provided with side guides and a central wearing-piece, which can be replaced. Fig. 12 is a view of a friction-brake provided with the V-groove edge. Fig. 13 is a side elevation of the device to take up the slack and provide for the wear of the friction-brake. Fig. 14 is a side view of Fig. 13. Fig. 15 is a sectional side elevation of a modified foot action, in which a cover is provided to prevent injury from dirt and dust, and at the same time permit free action of the moving parts of the foot. Fig. 16 is a cross-sectional elevation of Fig. 15. Fig. 17 is a perspective view of Fig. 15 without the covering. Fig. 18 is a sectional view of a tip in the plate of the foot action. Fig. 19 is a sectional side elevation of my foot action, showing the master-plate provided with a hot chamber for the purpose of filling with hot water, and also showing pointed calks or wearing-points.

Referring to the drawings, my triplex motor is provided with four driving-wheels, A, and these wheels are upon axles A' A''. The axles carry chain sprocket-wheels (shown in dotted lines) upon which is the chain A''. The axle A' is also provided with an additional

chain sprocket-wheel, A⁴, to which is applied the chain A⁵. The sprocket-wheel A⁶ of the friction-brake B is upon the outer case, B', of the said brake B, and the brake is on the shaft 5 C. There is a sprocket chain-wheel, of diameter equal to the case B', also on shaft C, and this connects with the chain A⁷, which is connected to the main driving-shaft D of the motor. On the main shaft D is the balance eccentric D', and this operates a bell-crank action, D², and this in turn operates a loop connection-rod, D³, and this operates the plunger of the pumps E. In this construction of motor the pumps E are in the front of the motor. 10 The pumps E are two sets of pumps to pump water, and this water, water and glycerine, or oil is pumped over and over again to operate two hydraulic cylinders, F, of the motor. The pistons of these hydraulic cylinders F are 15 connected with cross-heads F'. The cross-heads F' are connected by connecting-rods F² F³ to a foot action, F⁴. The foot action F⁴ is provided with a flat master-plate F⁵. This plate F⁵ is to carry the rubber cushions F⁶, F⁷, and F⁸ of the foot action. The master-plate has a projection downward, F⁹, through which passes the thrust-bolts F¹⁰, which are provided with the face-plates F¹¹ and F¹². These plates force onto the rubber and make an elastic thrust in the action of the foot. At the 20 end of the bolt F¹⁰ is the plate with flat hole F¹³, and through hole in the eye-plate is the bolt F¹⁴. This bolt F¹⁴ is the foot of the motor, and has the prongs f f f f—actually four to each 25 one foot. The bolt F¹⁴, passed through the rubber F⁶, which is of the shape indicated by Fig. 3, and the holes shown by f' f² f³ f⁴ allow the bolts F¹⁴ to be squeezed out of distances by the action of the motor walking or 30 running; but upon the foot being lifted from the ground it will again come into its proper shape.

Upon the top of the master-plate F⁵ is the connection G, which holds the T-shaped end 45 of the thrust-rod G' of the foot action. Where there are two rods they will be G' and G². This rod is connected at the top end by a clevis, G³, to a balanced beam, G⁴. This beam vibrates at g, and is connected by a cross-head, 50 G⁵, to an air-cylinder H. At the end of the beam G⁴ is the counterbalance-weight G⁶. The air-cylinder H is supplied with compressed air from the action of the main power of the motor, and the valve action (shown in dotted 55 lines) is of the ordinary stop action known in the church-organ, and is placed into action by the stop-lever H'.

At the side of the lever H', and nearly in line therewith, is the driving-lever I. This is connected with the hydraulic pumps E, and operates the supply of water to the pumps through the valve E'. In a line with this lever I is a 60 brake-lever, the connections to the brake-shoes, together with the shoes themselves, being shown in Fig. 1 in dotted lines.

At the side of the motor is a tank of water,

K, connected to the cylinder of a gas-engine for the purpose of keeping it cool, the warmer water being taken out of the top of the cylinder L and the colder returning in at the bottom thereof, so that a circulation of the water is maintained through its own well-known nature of movement due to heat.

Immediately in front of the water-tank is a tank, M. This tank is to receive a charge of 75 gas under high pressure, and to use this gas in the motor it is taken out of the tank at the first tap immediately in front of the tank, and by the pipe m' is conveyed to two T-couplings, m² m³. These connecting with stop-valves m⁴ m⁵ 80 immediately underneath gas regulator devices m⁶ m⁷. These have secondary taps m⁸ m⁹, and then the pipes m¹⁰ m¹¹ go into two T-couplings, m¹² m¹³, and these couplings supply the pipes m¹⁴ m¹⁵, and the division in the supply of gas 85 at m¹⁶ is for the purpose that, as the cylinder of a gas engine takes in a sudden suction of gas, if the lights for the gas-engine are on the same immediate supply as the cylinder, then the sudden suction will put these lights out. 90 By the construction of the double regulators the high-pressure gas comes to a full stop at the regulators and is not affected by the gas-engine's action, so that after the gas passes the regulators m⁶ m⁷ the two streams of gas 95 are independent and each do their respective duties. The pipe m¹⁴ is led to the back part of the motor and is carried into the bottom of a water-locked gasometer, n. This gasometer n has the regular stand-pipe inside and delivers 100 its regulated pressure gas to pipe n', and at n² this pipe enters pipe n³, which is provided with the elastic gas-bag N⁴. It will be seen that the pipe n³ goes into the pipe m¹⁴. This is so as to immediately take the regulated supply of city-pressure gas and yet be enabled to respond with a rapid supply of plenty of gas from the gasometer n when necessary. The pipe m¹⁵ can be treated in the same manner as the pipe m¹⁴ and the supply of gas delivered 105 at the pipes O, as shown in dotted lines.

The great difficulty in keeping the gas-engine cylinder cool in winter time is an advantage to the motor. A pump will be supplied and a system of rubber pipes led down 115 the thrust-rod G' of the engine to a hot-water chamber, P, Fig. 19. This will be kept above the freezing-point by this means, and the foot action come down sharp cut, and will not ball by the ice and snow. The covering P' is to prevent the dust from injuring the feet of the motor. The master-plate can be provided with 120 points, as shown in Fig. 18.

The friction part of my invention is designed to enable the driver of the motor to 125 place more or less power into the driving constructions of the motor; or, in other words, to give any desired force to the driving-wheels of the motor.

On the shaft C is the case B', and in the interior of this case is a projection, B², to which 130 is a bell-crank, B³, and lever B⁴. The end of

the lever B^4 has an eye, B^5 , forged onto it, and into this eye is another link, B^6 , forged, making a chain connection. The end of the link B^6 terminates in the clevis-jaws B^7 on the sleeve 5 B^8 . This sleeve B^8 has the annular groove, B^{16} , connection to allow for a movement in and out on the shaft C . The case B' also is provided with the cleat B^9 , and this cleat connects with the adjustable strap B^{10} . This strap passes 10 round a wheel, B^{11} , which is keyed by a key, B^{12} , onto the shaft C , so that the revolution of the shaft C is transmitted to the wheel B^{11} and to the case B' only when the sleeve B^8 is forced 15 along the shaft C . The connection B' causes the link B^6 and B^4 to rise, so as to move the crank B^3 . This crank is attached to the cleat B^2 , and this cleat is bolted to the cover B' , and the outer end of the crank B^3 is attached to the strap B^{10} . This strap is wound around the 20 wheel B^{11} , and the other end of the strap is attached to the cleat B^9 on the cover B' , and the action of the crank B^3 is to draw up tightly the strap, and by it tighten the shoes B^{13} on the wheel B^{11} . As the wheel B^{11} is keyed at 25 B^{12} to the shaft C , the tightening of the shoes B^{13} by the strap B^{10} , through the action of the before-mentioned parts, causes the motion that is in the shaft C to be transmitted to the cover B' , and by it to the chain-wheel A^6 , which is 30 attached to it. This strap B^{10} can be protected by a small counter-shoe, B^{14} , and held by pin, as shown in Fig. 10.

Figs. 11 and 12 represent constructions in which wheel B^{11} in Fig. 12 is provided with a 35 V -groove construction, and likewise the shoe which touches upon the same.

In Fig. 11 the shoe B^{13} is provided with guide-ears b b , the center of the shoe b^2 being of a soft substance, for the purpose of replacement 40 when worn out.

Figs. 11, 13, and 14 represent attachments to the lever B^4 , so that a wrench, B^{15} , can operate on the bell-crank B^3 , and in that way it can be tightened up on the strap B^{10} .

45 The motor hereinbefore set forth is to be operated by a gas-engine, which runs along, notwithstanding the motor may be stopped, and accumulates a pressure of air and water—the air to operate a cylinder, which places the foot action on the ground, and the water to force along the motor. Two feet of like construction are in the motor, being a double or duplex action of or for traction. In this motor there is an additional point, whereby the 50 triplex nature of the invention comes in play, so that there are two feet for traction purposes and a perfect set of coupled driving-wheels operated by a friction device at the will of the operator, giving the triplex motor three chances 55 of traction, the cohesion of the driving-wheel construction being worth one-fifth of the weight of motor for its traction-pull on a slippery rail, one-tenth of the weight on a slippery rail, and on a curve but one-twentieth. The duplex feet action of the motor of the traction is 60 so regulated by the pressure which is given by

the cylinder H that the traction will be steadily held at two thousand pounds; and it is possible in this system of motor to use instead of the gas-engine the following powers: Steam, 70 electricity, either by taking up the power from a charged rail or by storage-battery, vacuum-engine, high or low pressure compressed air, ammoniacal gas, chloride of calcium, bisulphate of carbon, tank of hot water understeam pressure to give off its steam for use on the journey, carbonic acid, compressed soda-ammonia, or petroleum-engine, any of which powers can operate my motor.

Having thus described the construction and 80 operation of my invention, what I claim as new, and desire to secure by Letters Patent of the United States, is—

1. The shaft C , provided with a friction-wheel keyed thereon, and the said wheel enveloped by a case free to revolve in connection with the driving-wheels of the motor, said case provided with projections B^2 and B^9 , to retain and sustain an adjustable strap, B^{10} , operated by the bell-crank B^3 , and adjustable lever-arm 85 B^4 , connected to a link and clevis, and sleeve B^8 , that rests and slides on shaft C , the case connected to the friction-wheel by tightening the said strap thereon to apply the revolution of the shaft C to the case and its connections 90 to the driving-wheels of the motor, combined and operated substantially as shown and described.

2. The shaft C , provided with a single friction-wheel keyed thereon and enveloped by a 100 case, said case provided with an adjustable strap having shoes B^{13} and counter-shoes B^{14} , and operated by the adjustable lever, and sliding sleeve to apply power of the moving shaft C through the enveloping-case to the driving-wheels of the motor, substantially as and for 105 the purpose set forth.

3. In a motor or other vehicle, the friction-wheel and strap-operating mechanism to operate the driving-wheels of the motor, and a foot-action mechanism to give additional traction from the power of the moving engine on the motor, combined in one motor or upon one dummy, substantially as and for the purpose set forth.

4. The combination, in a motor provided with a foot mechanism, of a thrust-rod connected to a counterbalanced lever adapted to raise and lower the foot mechanism operated by connecting-rods, substantially as shown, 115 and operated as and for the purposes described.

5. The foot mechanism for a traction-engine or street-car motor provided with a warming-space for holding hot water, hot air, or gas, 120 substantially as and for the purpose set forth.

6. The foot mechanism of a street-motor or traction-engine provided with a rubber cushion adapted to act elastically upon a row of claws, substantially as and for the purpose set 125 forth.

7. In a street-car motor or traction engine

provided with a tank of high-pressure gas, which is regulated to city pressure, which is the motive power of the motor, the double gas-regulators to supply the double streams of regulated gas to the cylinders and flame-lights of the gas-engine, substantially as herein described, and for the purposes set forth.

8. The foot mechanism of a street-motor or traction-engine, the T-connection of the thrust-lever G', connected to the plate F⁵, substantially as shown and described.

9. The foot mechanism of a street-motor or traction-engine provided with rubber cushions

to act elastically upon one or more thrust-bolts attached to the claws, substantially as shown 15 and described.

10. The friction-brakes provided with the strap, and shoes operated by the sleeve B¹⁶ through connections B⁶ and B⁴, and crank B³, substantially as set forth.

In testimony whereof I affix my signature in presence of two witnesses.

BENJAMIN C. POLE.
